UNITED STATES PATENT OFFICE.

BEN E. GORDON AND LLOYD HATCHER, OF TRINIDAD, COLORADO.

DESIGN FOR A SIGNAL.

Application filed January 15, 1929. Serial No. 29,623. Term of patent 7 years.

To all whom it may concern:

Be it known that we, BEN E. GORDON and LLOYD HATCHER, citizens of the United States of America, and residents of Trinidad, in the county of Las Animas and State of Colorado, have invented a new, original, and ornamental Design for a Signal, of which the following is a specification, reference being had to the accompanying drawing, forming part thereof.

Figure 1 is a front elevation of a signal, showing our new design, and

Figure 2 is an edge elevation thereof.

We claim:

The ornamental design for a signal, as shown.

BEN E. GORDON.
LLOYD HATCHER.
